UNITED STATES PATENT OFFICE

NAJEEB J. SAAD, OF SPOKANE, WASHINGTON

KEY LOCKING LOCK

Application filed May 24, 1932. Serial No. 613,173.

My invention relates to key locking locks and certain objects of the invention are to provide a lock having means whereby a key that is used to lock and unlock doors of lockers, closets and the like is caught and retained in the lock when a door is unlocked and is thus prevented from being removed or withdrawn from the lock except by means of a second key which may be in the custody of an official or other authorized person. The device is particularly adapted for use in checking rooms and the like and by its use keys may be safely left in the locks of doors while they are unlocked thus obviating the necessity of turning the keys over to an official each time the lockers are used, or eliminating the necessity of carrying the keys around and the consequent danger of losing the keys.

With the above and other objects in view which will appear as the description proceeds, the invention consists of the novel construction, adaptation, combination and arrangement of parts hereinafter described and claimed. These objects are accomplished by the devices illustrated in the accompanying drawing; wherein: Figure 1 is a view in perspective showing a lock with its casing cover removed and embodying the features of the invention; Fig. 2 is a view in vertical section taken substantially on a broken line 2—2 of Fig. 1; Fig. 3 is a fragmentary detail view in elevation showing a key in its movement past the key locking means when a door is locked by the main locking bolt; and Fig. 4 is a corresponding view showing the key locked by the key locking means when a door is unlocked.

Referring to the drawing throughout which like reference numerals indicate like parts, the numeral 5 designates a lock casing having a cover member 6 secured thereto and a locking bolt 7 and sliding levers 8 mounted therein with the usual actuating springs 9. A key 10 is adapted to be inserted into a keyhole 11 and used for locking and unlocking the lock when the key is turned to the left or right to slidably move the levers and the bolt in the usual manner. The foregoing elements form no part of my invention but necessarily enter into combination there-

with. It will however be understood that said elements may be of any form, arrangement and combination that will function in the operation of my invention which will now be described.

Essentially my invention comprises a lever member 12 with a cylinder 13 fixed to its lower end and pivoted within the lower portion of the casing 5. Said cylinder is provided with a key recess 14 that is adapted to receive a second key 15, as shown in Fig. 2, when same is passed into a hole 16 through the casing. A leaf spring 17, fixed to said cylinder and bearing against a side of the casing, is adapted to normally retain said lever member in a vertical position against a stop pin 18 fixed to the casing. A jaw 19 is fixed to the upper end portion of the lever 12 and a corresponding jaw 20 is pivoted at 21 to said lever a short distance below the fixed jaw. The outer ends of said jaws project in a direction toward the keyhole 11 and are oppositely beveled, or in other words the fixed jaw 19 has its end beveled downwardly and outwardly while the pivoted jaw 20 has its end beveled upwardly and outwardly. The pivoted jaw may be slightly longer than the fixed jaw if desired, and a small leaf spring 22 normally retains the pivoted jaw in parallel spaced relation with the fixed jaw and against a stop pin 23 fixed to the lever member.

When locking a door to which the device is fixed the key 10 is turned to the left, or counter clockwise, in the regular manner as indicated by the direction arrow in Fig. 3. In its turning movement to the left said key engages the outer beveled end of the pivoted jaw 20 pivotally raising said jaw, overcoming the tension of the small leaf spring 22 and forcing said pivoted jaw against the fixed jaw 19 whereby the key is prevented from being caught between said two jaws as will be understood. In its continued movement to the left and in engagement with the outer beveled end of the pivoted jaw 20, the lever member 12 is pivotally moved back against the tension of the leaf spring 17 and when the key passes said lever member the leaf springs 17 and 22 will return said lever member and its pivoted jaw 20 to their respective normal

positions. The key then passes on to the left engaging the sliding levers 8 and thus causing the bolt 7 to move to the outward or locked position.

5 Referring now to Fig. 4, in unlocking the door to which the device is secured, the key 10 is turned to the right, or clockwise, in the regular manner as indicated by the direction arrow. Assuming that the key has already 10 moved the bolt 7 inwardly whereby the door is unlocked, said key will then, in its continued movement to the right, engage the beveled end of the fixed jaws 19 and thus pivotally move the lever member 12 back to the 15 dotted position against the spring 17. Then in its continued movement to the right the key will be lodged or caught by the outer projecting end of the pivoted jaw 20 and the spring 17 will forthwith move the lever 20 member 12 back to its vertically normal position thus catching and locking the key between the jaws 19 and 20. Now in order to remove the key 10 from the lock it is necessary to again move the lever member 12 to the right 25 to release the key from the jaws and this is done by inserting the second key 15 into the recess 14 of the cylinder 13. The second key may be in the custody of a check room official or other authorized person and it will now 30 be apparent that, by means of my device, keys may be safely left in the locks of closet or locker doors when the doors are left in the open or unlocked position.

Having thus described my invention, it 35 being understood that minor changes in its construction and arrangement may be resorted to without departing from the scope and spirit of the invention, what I claim and desire to secure by Letters Patent of the 40 United States is:—

1. The combination with a lock comprising a bolt operable by a key for slidably moving the bolt to the locked and unlocked positions, of key locking means comprising a lever member pivotally mounted within the lock and having a recess adapted to receive a second key, a beveled jaw fixed to the free end of the lever member, a spring actuated jaw pivotally connected to the lever in normally spaced apart relation with the fixed jaw, a spring arranged to normally retain the lever in a position whereby its jaws are engageable by the first key and whereby said lever and jaws are moved out of the way when the first key is turned to lock the bolt, and said jaws adapted to catch and retain the first key after it is turned to unlock the bolt and whereby it is necessary to move said lever by means of a second key inserted in its recess in order to release the first key.

2. In a key locking lock comprising a bolt operable by a key for slidably moving the bolt to the locked and unlocked positions, the combination of key locking means comprising a lever member having a cylinder fixed to one

end and a beveled jaw fixed to its other end, said cylinder pivoted within the lock and having a recess adapted to receive a second key, another beveled jaw pivoted to the lever, a spring with means for retaining the pivoted jaw normally in parallel spaced apart relation from the fixed jaw, another spring arranged to normally retain the lever with its jaws in engageable relation with the first key and whereby said jaws are moved out of the way by the first key when it is turned to lock the bolt, and said jaws adapted to catch and retain the first key after it is turned to unlock the bolt and whereby it is necessary to move said lever member by means of a second key inserted in the recess of its cylinder in order to release the first key.

In testimony whereof I affix my signature.

NAJEEB J. SAAD.
